GUNSIGHT

Olle Edstrom, Langgatan 18, 82700,
Ljusdal, Sweden

Filed Oct. 5, 1973, Ser. No. 403,902

Claims priority, application Sweden, Apr. 10, 1973

Term of patent 14 years

Int. Cl. D16—06

U.S. Cl. D22—8

FIG. 1

FIG. 2

FIG. 4

FIG. 3

FIG. 1 is a perspective view, showing a gunsight embodying my new design;

FIG. 2 is a rear side elevation of the gunsight of FIG. 1;

FIG. 3 is a rear end elevation of the gunsight of FIG. 1;

FIG. 4 is a bottom view of the gunsight of FIG. 1.

I claim:

The ornamental design for a gunsight, as shown.
